UNITED STATES PATENT OFFICE.

SAMUEL J. RECKENDORFER, OF NEW YORK, N. Y.

DESIGN FOR A DISPLAY-SIGN.

No. 38,641.

Specification for Design.

Patented June 25, 1907.

Application filed April 8, 1907. Serial No. 367,131. Term of patent 7 years.

To all whom it may concern:

Be it known that I, SAMUEL J. RECKENDORFER, a citizen of the United States, residing in the city and State of New York, whose post-office address is 45 West Fifty-sixth street, New York, have invented a new, original, and ornamental Design for a Display-Sign, of which the following is a specification, reference being had to the accompanying drawing, forming a part thereof.

The figure represents a perspective view of a display sign showing my design.

I claim,—

The ornamental design for a display sign as shown.

SAM. J. RECKENDORFER.
